UNITED STATES PATENT OFFICE.

ALFRED HAVILAH WOODWARD, OF BIRMINGHAM, COUNTY OF WARWICK,
ENGLAND.

PENCIL, PEN, OR TOOTH-PICK CASE.

SPECIFICATION forming part of Letters Patent No. 296,302, dated April 1, 1884.

Application filed December 12, 1883. (No model.) Patented in England November 2, 1883, No. 5,224.

To all whom it may concern:

Be it known that I, ALFRED HAVILAH WOODWARD, a subject of the Queen of Great Britain, residing at Birmingham, in the county of Warwick, England, have invented certain new and useful Improvements in Pencil, Pen, or Tooth - Pick Holders; and I hereby declare the following to be a full, clear, and exact description of the same, such as will enable others skilled in the art to make and use it, reference being had to the accompanying drawings, in which—

Figure 1 represents a pencil, pen, or tooth-pick case constructed according to my improvements, with the point retracted. Fig. 2 is an elevation of the same, partly in section, showing the point projected. Fig. 3 is an elevation, with the outer casing in section, the point being retracted. Fig. 4 is an elevation, the outer casing being in section and the point projected. Figs. 5, 6, and 7 are detail views, showing the device in its various positions. Figs. 8, 9, 10, 11, 12, and 15 are detail views of the various parts. Figs. 13 and 14 are sectional views of modifications.

My invention has relation to pencil, pen, or tooth-pick cases or holders, in which the portion holding the lead or other writing material, pen, or tooth-pick can be automatically projected from or withdrawn into its case or holder.

My invention consists in the novel construction and combination of parts, whereby the impelling of the point or nozzle of the device is effected by pressing upon the cap at the end of the pencil, and its retraction effected by rotating the said cap.

My invention comprises, briefly, an exterior casing having at one end a sliding cap, which, being pressed down, impinges upon a movable mount, and projects the latter out through the other end of said casing, an automatic catch operating to hold the mount in its projected position during use, its retraction being effected by releasing said catch by turning the said cap, as hereinafter set forth.

Referring to the drawings, A represents the exterior casing of the pencil. B is the movable cap, sliding within the case A, and im-

ping upon the shaft C of the mount C². Said shaft C has a head, C⁴, that slides within a casing, D, which is attached to and forms part of a plug, D⁴, at the lower end of casing A. The head C⁴ has a pin, C³, that works in a bayonet-slot, D² D³, in the upper part of the casing D, and is provided with a slot, C⁵, that receives the upturned end of a spiral spring, F, which surrounds the shaft C of the movement, and is attached at F³ to the plug D⁴.

The cap or pusher-mount B consists of a tube, closed at its upper end and provided at its bottom with a collar, B⁶, which has an open L-shaped slot that receives the end E³ of a spiral spring, E, surrounding the casing D, and attached at F³ to the plug D⁴. Above the collar B⁶ and integral with the cap B is a second collar, B⁵, and between the collars B⁵ and B⁶ the cap B is cut out to form a triangular slot having two inclined sides, B³ B⁴, and a straight side, B¹. The portion of the cap B between the collars B⁵ B⁶, I have called the "impelling-tube" and designated by the letter B². The pin C³ upon the head of shaft C projects through the slot in the impelling-tube, as well as through the slot D² D³ of casing D, and within the said impelling-tube, above the top of the triangular slot, is fixed a cushioned plug, G, against which the head C⁴ strikes when the movement is retracted, thereby preventing injury to the pin C³.

The operation of my invention is as follows: Upon pressing upon the cap B the top edge, B³, of the slot in said cap presses upon and forces forward the pin C³ down the conducting-slot D² of the fixed conductor-tube D, and on the pin C³ traveling to the bottom thereof bears against the inclined upper edge, B⁴, of the impelling-tube slot, and on coming opposite the inclined slot D³ turns into said inclined slot and fixes the movement in position for use, the cap B returning to its original position by the expansion of spring E, the pin C³ remaining at the end of the slot D³, as shown in Fig. 2. To retract the movement it is only necessary to turn the cap B about a quarter-revolution to the left. This forces the pin C³ out of slot D³ and into slot D², and the movement returns to its original position by the ex-

pansion of spring F. I would here remark that when the pen or pencil is being put together the spring F is given a twist to the left before fastening it in position in the slot C⁵; 5 hence the movement C has a constant tendency to turn to the right, so that when it reaches the bottom of the slot D² the torsion of the spring F will cause the spring C³ to assume the position shown in Figs. 2 and 5. 10 The spring E is also twisted before being placed in position, and has the effect of turning the cap B from left to right, thereby further assuring the locking of the movement in its projected position. 15 In the modification shown in Figs. 13, 14, and 15, the relative position of the parts is somewhat changed; but the principle and operation are substantially the same as in the device hereinbefore described. In the said modification the movement is composed of two parts, C and D, connected together by the spring F, the parts C carrying the locking-pin C³, and the part D being fixed in the casing. The position of the spring E is also changed, 25 it being placed within the top of cap B and resting on the conducting-tube D. The mode of operation is as before, the spring F acting by expansion and contraction, instead of by compression and recoil. 30 Having fully described my invention, I claim—

1. In a pencil, pen, or tooth-pick holder, the combination, with an exterior casing and a movable cap, of a movable mount, adapted 35 to be projected from the holder, and means, as set forth, whereby said mount is automatically

locked in such projected position by depressing said cap, and to be released from such locked position by revolving the cap, substantially as described. 40

2. In a pencil, pen, or tooth-pick holder, the combination of an exterior casing and a movable cap, with a movable mount capable of independent movement with relation to said cap, by means substantially as set forth, and 45 adapted to be projected from the casing and automatically locked in such projected position by depressing said cap, and a coiled spring, which will retract said mount when the cap is revolved, substantially as described. 50

3. In a pencil, pen, or tooth-pick holder, the combination of an exterior casing, a slotted interior casing, and a slotted movable cap, with a movable mount having a pin which projects through the slots in the cap and the 55 interior casing, and, when the mount is projected, engages with a lateral slot opening into said slot in the interior casing, substantially as described.

4. In a pencil, pen, or tooth-pick holder, 60 the combination of exterior casing, A, and movable cap B, having a triangular slot, B³, and spring E, with the interior casing or tube, D, having bayonet-slot D² D³, and mount C, having pin C³ and spring F, substantially as 65 described.

ALFRED HAVILAH WOODWARD.
